UNITED STATES PATENT OFFICE

JAMES E. DUNCAN, JR., OF WASHINGTON, PENNSYLVANIA, ASSIGNOR TO THE DUNCAN & MILLER GLASS COMPANY, OF WASHINGTON, PENNSYLVANIA, A CORPORATION OF PENNSYLVANIA

DESIGN FOR A TUMBLER OR LIKE ARTICLE

Application filed August 6, 1930. Serial No. 36,577. Term of patent 14 years.

To all whom it may concern:

Be it known that I, JAMES E. DUNCAN, Jr., a citizen of the United States, residing at Washington, in the county of Washington and State of Pennsylvania, have invented a certain new, original, and ornamental Design for Tumbler or like Article, of which the following is a specification, reference being had to the accompanying drawing, forming a part hereof.

The single figure is a side elevation partly in perspective of the article, showing my new design.

I claim:

The ornamental design for a tumbler or like article as shown.

In testimony whereof I have hereunto subscribed my name this 1st day of August, 1930.

JAMES E. DUNCAN, JR.
